Term of patent 7 years

(Cl. D45—4)

FIG. 1

FIG. 2

FIG. 3

FIG. 4

FIG. 1 is a top plan view of a link chain for a bracelet showing my new design;

FIG. 2 is a side elevational view of the link chain of FIG. 1; and

FIGS. 3 and 4 are end elevational views on an enlarged scale of individual top shells of the link chain of FIG. 1 taken respectively along the lines 3—3 and 4—4 of FIG. 1.

The shading in FIG. 1 indicates contrast.

This application is a division of my application Ser. No. D. 72,792, filed December 10, 1962.

I claim:

The ornamental design for a link chain for a bracelet or the like, as shown and described.
